UNITED STATES PATENT OFFICE.

RICHARD A. BURY AND ROBERT M. BIDELMAN, OF ADRIAN, MICHIGAN.

DEVICE FOR BURNING PETROLEUM.

SPECIFICATION forming part of Letters Patent No. 268,077, dated November 28, 1882.

Application filed September 16, 1882. (No model.)

To all whom it may concern:

Be it known that we, RICHARD A. BURY and ROBERT M. BIDELMAN, of Adrian, in the county of Lenawee and State of Michigan, have invented new and useful Improvements in Devices for the Use of Petroleum as Fuel; and we hereby declare that the following is a full, clear, and exact description thereof, reference being had to the accompanying drawings, which form a part of this specification.

The nature of this invention relates to certain new and useful improvements in devices for burning petroleum or other suitable oils of analogous character for heating purposes.

The invention consists in the means for accomplishing the purpose, as more fully herein-after described.

Figure 1 is a cross-section of an ordinary cook-stove. Fig. 2 is a detached perspective of the deflecting porous shield.

In the accompanying drawings, which form a part of this specification, our invention is shown as applied to the fire-box of a cook-stove; but we do not desire to confine ourselves to this particular class, as it is self-evident that our invention may be employed with great benefit in the furnaces of locomotives, stationary boilers, heating-stoves, and furnaces.

A represents the fuel-chamber of the stove. The grate-surface of the fire-box or the position occupied by the grate is filled with a sheet of asbestos, B, which may be supported by the grate, or in any other suitable manner. A deflecting and distributing shield, C, is placed, standing substantially in the position shown in the fire-box, so that a circulation may be obtained all around it. This shield is supported upon brackets D, or in any other suitable manner which will allow of the circulation.

E is a feed-pipe extending through the wall of the furnace and connecting with an elevated reservoir, and this pipe is provided with a small orifice at a, through which the contents of the elevated reservoir are discharged against the shield. The object of elevating the reservoir is to obtain a forcible discharge in this small jet, or the same result may be obtained by a sufficient pressure of air in the reservoir.

The asbestos of which the shield is formed being in fiber becomes a distributor or absorbent of the oil injected against its face, and is held in place and formed as shown by means of a wire covering adapted for the purpose, and this covering will last indefinitely, as the only point where it will be destroyed is immediately about the point against which the jet impinges.

In practice, when it is desired to light the fire a stop-cock, b, in the feed-pipe is opened, and the petroleum therein is forcibly ejected in a very small jet against the side of the shield. A match is now applied to the surface of the shield and the oil ignited, as the fire increases in heat and burns with an intense flame, giving but very little smoke, not sufficient to render the use of this class of fuel at all objectionable. In its use no change in the construction of the furnaces is required except to accommodate the pipe E.

We are aware that many processes have been invented and experimented with for the purpose of economically utilizing evaporizing oils, like crude petroleum for heating purposes, and hence we do not broadly claim the use of such material. We are unaware, however, that asbestos has been used as an absorbent vaporizer for this purpose; hence

What we claim as our invention is—

1. In combination with an elevated reservoir and a pipe leading therefrom having a regulating-cock and a contracted discharge-orifice, a shield or wick of asbestos held in contact or juxtaposition with such orifice, whereby the body of oil is separated from the wick and the flow of such oil may be regulated at will, as set forth.

2. In combination with the fire-box of a stove or furnace, the elevated reservoir having pipe E, cock b, and jet a, the shield C of asbestos having wire-cloth covering, and the folding wire D, as and for the purposes set forth.

RICHARD A. BURY.
ROBERT M. BIDELMAN.
